APPARATUS FOR WINDING HAIR

James McAdie, Dublin, Ireland

Application November 4, 1936, Serial No. 109,145
In Great Britain November 6, 1935

10 Claims. (Cl. 132—33)

My invention relates to an apparatus for use by hairdressers in the process of permanently waving human hair wherein the tress of hair to be waved is tightly wound upon a curler and then subjected to further treatment.

Appliances for winding hair for permanent waving are known wherein rotation and movement of the appliance axially of a curler causes a tress of hair to be wound along the length of the curler.

The object of the present invention is to provide an apparatus, operated by hand or mechanically, which quickly and smoothly winds a tress of hair on a curler and enables the tress so wound to be maintained on the curler. The whole operation of winding and maintaining the hair on the curler is carried out much more expeditiously and effectively than hitherto and the tension and pitch of the curl of hair may be altered as desired.

The apparatus according to the present invention is characterised by a tubular casing open at one or both ends, a curved member positioned partly within the casing adapted to exert a variable pressure on a curler and to smoothly apply a tress of hair thereto, and means attached to the exterior of the tubular casing to carry a roll of gauze or similar material to maintain the hair coiled on the curler.

The apparatus is further characterised by a slidable cursor which causes the curler to be clamped within the tubular casing and by means of which the tension and pitch of the curl of hair wound on the curler may be regulated.

Additional features of the invention will be set out and in order that the invention may be more clearly understood and readily carried into effect it will now be described having reference to the accompanying drawing, in which—

Fig. 1 is a horizontal elevation of the apparatus.

Fig. 2 is a plan of the apparatus viewed from the end opposite the handle.

Fig. 3 is a horizontal section along the centre line of Fig. 1.

Fig. 4 is a view of the apparatus on a reduced scale showing a tress of hair about to be wound on a curler.

The same reference numerals refer to the same parts throughout.

Referring to the drawing the apparatus comprises a tube 1 of any suitable material such as brass, aluminium or the like, open at its end 2; the opposite end of the tube 1 may be closed and if desired be provided with a handle 3, as

shown in Figs. 1 and 4. Attached to the exterior wall of the tube 1 at a point adjacent to the handle 3 is one end of a flat spring 4 (Fig. 3) which extends on the outside of the tube 1 to substantially as far as the open end 2 of the latter, where it is bent over towards and passes into the interior of the tube through an appropriate opening 5 in the wall thereof. The spring 4 is shaped substantially as shown in Fig. 3.

The end of the spring 4 situated within the tube 1 carries a relatively short plate 6 positioned approximately parallel to the axis of the tube 1 and having one of its ends projecting slightly beyond the end 2 of the said tube 1. The plate 6 is curved as indicated in Fig. 2. 15 A slide or cursor 7 encircles the tube 1 and is freely slidable thereon; when moved towards the open end 2 of the said tube it compresses portion of the spring 4 towards the exterior wall of the tube and causes the curved plate 6 to 20 be resiliently pressed towards the opposite interior wall of the tube 1. The opening 5 through which the spring 4 passes into the interior of the tube 1 is such as to allow the minimum of play to the said spring 4 so as to prevent excessive lateral movement of the curved plate 6. 25 A slot 8 is cut in the wall of the tube 1 parallel to the axis thereof, and diametrically opposite the flat spring 4, the sides of the said slot for approximately one half its length being splayed 30 out as they approach the open end 2 as indicated by reference numeral 9.

Attached to the exterior wall of the tube 1 adjacent to one of the splayed out edges 9 of the slot 8 is a member 10 consisting of a light 35 section round wire helically wound, which serves as a guide for the tress of hair 21 to be curled. Secured to the exterior wall of the tube 1 adjacent to the open end 2 and symmetrically positioned with regard to the slot 8 is a curved bridge 40 piece 11 which passes over portion of the spring 4. Mounted on that side of the bridge piece 11 adjacent to the aforementioned helical guide 10 is a support 12 carrying a bobbin of gauze 13 for a purpose to be hereinafter described; and 45 so positioned that the central spindle of the bobbin 13 is substantially parallel to the face 17—18 of the bridge piece 11.

Attached to the bridge piece 11 as shown in Fig. 3 is a flat spring 14 the free end 15 of 50 which carries centrally pivoted a narrow metal strip 16 which is thus caused to bear evenly on the surface 17—18 of the bridge piece. The spring operated bearing plate 16 guides and causes a tension to be exerted on the gauze 55

which is subsequently to be passed under it. The axis of the bobbin of gauze 13 and the surface 17-18 of the bridge piece are fixed at an acute angle to the longitudinal axis of the tube 1 as 5 illustrated in Figs. 3 and 4 to facilitate the even application of the gauze to the tress of hair wound on the curler.

In operating the apparatus a curler 19 is inserted into the tube 1 as shown in Fig. 4 with its 10 split end 20 projecting a convenient distance beyond the open end 2 of the tube. A tress of the hair 21 to be curled is attached to the split end 20 of the curler in the usual manner. The cursor 7 is then moved forward towards the end 15 2 of the tube 1 compressing the flat spring 4 and clamping the curler 19 with the attached tress of hair 21 between the interior wall of the tube 1 and the curved plate 6. That portion of the tress 21 to be curled which is adjacent to the end 20 of the curler is drawn through the splayed out opening 9 in the wall of tube 1 and the remainder 20 of the tress to be curled is passed through the helical windings of guide 18 as shown in Fig. 4. The roll of gauze 13 shown in Fig. 1 is omitted 25 from Fig. 4 for the sake of clarity in the drawing. The projecting end 20 of the curler 19 is then held stationary in one hand of the operator and the apparatus is rotated in an anti-clockwise direction about the curler by the other hand or 30 by any known mechanical means whereupon the tress of hair 21 passes under the curved plate 6 and is wound helically on the curler away from the end 20. The curved plate 6 causes the tress of hair to be applied smoothly and evenly to the curler.

As the tress of hair 21 begins to wind upon the curler 19, the end of the curved plate 6 adjacent to end 20 of the curler is forced back from the curler owing to the increased thickness of hair at 40 that end; a force acting longitudinally on the curler results which propels the apparatus along the curler as the rotation is continued. In the illustration shown the apparatus is rotated in an anti-clockwise direction as viewed from the handle end. The pressure of the curved plate 6 on the curler 19 or on the tress of hair wound on the curler may be varied by altering position of the 45 slide cursor 7 and the tension or pitch of the coils of the hair on the curler may also be regulated by the same means.

When the tress 21 has been wound on the curler 19 to the desired extent the roll of gauze 13 which has been impregnated with a suitable adhesive substance and previously damped has its free end carried under the narrow flat strip 16 on the bridge piece 11, then brought round the far side of the latter, passed under the tube 1, and through its splayed out end 9, and laid over and maintained by the thumb on that portion of the tress 21 adjacent to the projecting end of the small plate 6 carried by the spring 4. Further rotation of the apparatus around the curler 19 causes the end of the gauze to pass underneath the curved plate 6 and to be wound tightly over the remaining portion of the tress which has still to pass under the curved plate 6. The adhesive gauze is thus wound tightly on that end of the tress and on the bare portion of the curler adjoining and maintains the whole tress firmly on the curler for 55 subsequent operations. When sufficient of the gauze has been wound on the hair and curler the gauze is severed from the bobbin 13 and the pressure on the curler is released by sliding back the cursor 7 towards the handle 3. The curler 19 with the tress 21 wound and secured thereon is

then removed from the apparatus and the coiled tress may be further tightened on the curler by known means provided in the curler itself.

I claim:

1. An appliance for winding, tensioning and 5 maintaining a tress of hair on a curler comprising a tube for the reception of a curler and having at an open end a splayed out longitudinal slot, a flat leaf spring positioned outside the tube longitudinally thereof, a narrow curved plate secured to 10 said spring and positioned longitudinally partly within the tube, an annulus slidable on the exterior surface of the tube adapted to exert variable pressure on the leaf spring, a bridge piece on the exterior of the tube carrying a support for 15 a binding material, and a helical guide secured to the tube adjacent to the splayed out slot.

2. An appliance for winding, tensioning and maintaining a tress of hair on a curler comprising 20 a tube for the reception of a curler to one end of which the tress of hair to be wound has been attached and having at an open end a splayed out longitudinal slot, a flat leaf spring positioned outside the tube longitudinally thereto, one end of the said spring being attached to the exterior 25 wall of the tube adjacent its unslotted end whilst the other end is bent to pass through a narrow aperture in the tube wall, a narrow curved plate secured to said spring and positioned longitudinally partly within the tube, an annulus slidable 30 on the exterior surface of the tube and adapted to exert a variable pressure on the leaf spring, a bridge piece on the exterior of the tube carrying a support for a binding material, and a helical guide secured to the tube adjacent to the splayed 35 out slot.

3. An appliance for winding, tensioning and maintaining a tress of hair on a curler comprising 40 a tube for the reception of a curler and having at an open end a splayed out longitudinal slot, a flat leaf spring positioned outside the tube longitudinally thereto and diametrically opposite the aforesaid slot, one end of the said spring being attached to the exterior wall of the tube adjacent its unslotted end whilst the other end is bent to 45 pass through a narrow aperture in the tube wall, a narrow curved plate secured to said spring and positioned longitudinally partly within the tube, the plate being curved to partly embrace a curler inserted into the tube and to clamp it against the 50 opposite interior wall of the tube, a sleeve slidable on the exterior surface of the tube and engageable with a portion of said spring to exert a variable pressure on the leaf spring, a bridge piece on the exterior of the tube carrying a support for a binding 55 material, and a helical guide secured to the tube adjacent to the splayed out slot.

4. An appliance for winding, tensioning and maintaining a tress of hair on a curler comprising 60 a tube for the reception of a curler and having at an open end a splayed out longitudinal slot, a flat leaf spring positioned outside the tube longitudinally thereto, a narrow curved plate positioned partly within the tube and partly embracing a curler inserted into the tube, a sleeve 65 on the exterior surface of the tube slidable over part of the leaf spring, the movement of the sleeve causing the narrow curved plate carried by the spring to exert a variable pressure on the tress of hair wound on the curler, a bridge piece 70 on the tube carrying a support for a binding material, and a helical guide one end of which is secured to the tube adjacent to the splayed out slot.

5. An appliance for winding, tensioning and maintaining a tress of hair on a curler comprising 75

ing a tube for the reception of the curler and having at an open end a splayed out longitudinal slot, a flat leaf spring attached longitudinally to the exterior of the tube, a narrow curved plate 5 secured to said spring and positioned partly within the tube and partly embracing a curler inserted therein, a sleeve on the exterior surface of the tube slidable over part of the leaf spring thereby regulating the tension and pitch of the 10 tress of hair wound on the curler, a bridge piece attached to the exterior of the tube symmetrically with and diametrically opposite to the splayed out slot, a support on said bridge piece for a bobbin of gauze or like binding material, and a helical guide one end of which is secured to the tube 15 adjacent to the splayed out slot.

6. An appliance for winding, tensioning and maintaining a tress of hair wound on a curler comprising a tube for the reception of a curler 20 and having at an open end a splayed out longitudinal slot, a flat leaf spring positioned outside the tube and longitudinally thereto, a narrow curved plate secured to said spring and positioned longitudinally partly within the tube, a sleeve 25 slidable on the exterior surface of the tube and engageable with said spring to exert a variable pressure on the leaf spring, a bridge piece attached to the exterior of the tube, a spring-operated bearing plate on said bridge piece which 30 guides and causes a tension on binding material passing thereunder, and a helical guide secured to the tube on the same side as a bobbin of binding material and adjacent to the splayed out slot.

7. An appliance for winding, tensioning and 25 maintaining a tress of hair on a curler comprising a tube for the reception of a curler with a tress of hair attached to its projecting end, a splayed out longitudinal slot at the open end of the tube, and a helical guide secured to the tube 40 adjacent to said longitudinal slot through which slot and guide the tress of hair is drawn to be passed around the curler and under a narrow curved plate positioned longitudinally partly within the tube and carried by the free end of a flat leaf spring which is passed into the interior 45 of the said tube, a cursor slidable on the exterior surface of the tube by means of which a variable pressure is exerted on the leaf spring and transmitted through the curved plate to the tress of

hair being wound on the curler, a bridge piece attached to the exterior of the tube symmetrically with and diametrically opposite the splayed out horizontal slot and carrying a support for a bobbin of adhesive gauze or like material which is passed through said slot and wound to maintain the hair on the curler. 5

8. An appliance for winding, tensioning and maintaining a tress of hair wound on a curler as 10 claimed in claim 7, wherein the adhesive gauze or like binding material is carried underneath a spring-operated bearing plate mounted on the bridge piece being guided and tensioned thereby, the gauze being then continued around under the tube and passed through the splayed out longitudinal slot and then wound tightly underneath the curved plate over the end of the tress to 15 maintain the latter on the curler.

9. Apparatus for winding hair on a curler rod 20 comprising a tubular member having an open outer end, a handle on the opposite end of said member, said member having a longitudinally extending slot opening through the outer end thereof, a tensioning member disposed within said tubular member, an elongated spring secured at 25 one end to said tensioning member and projecting outwardly of said slot and longitudinally of said tubular member, a sleeve slidable on said tubular member and engageable with said spring upon outward movement thereof to tension said spring, 30 a U-shaped supporting member having the parallel legs thereof secured to said tubular member, said supporting member straddling said spring, and means secured to one side of said supporting member for supporting a gauze supply 35 roll.

10. An appliance adapted for use in connection 40 with a curler for winding, tensioning and maintaining a tress of hair on the curler comprising a tube for receiving the curler, and combined 45 means carried by the tube for clamping the curler against an interior wall of the tube and for causing the tress of hair to be applied smoothly and evenly to the curler, said means upon rotation of the appliance being urged away from the curler whereby a force acts longitudinally on the appliance to propel the appliance along the curler. 45

JAMES McADIE.
